UNITED STATES PATENT OFFICE.

CHARLES HUBBARD BERRY, OF MANSFIELD, OHIO.

BALL COCK.

Application filed March 2, 1926. Serial No. 91,745.

This invention relates to improvements in ball cocks for water closet tanks or the like.

One of the objects of the invention is to provide means whereby the plunger, its associated parts and operating mechanism can be removed from the body portion of the apparatus in its entirety, or replaced therein.

Another object is to provide means whereby the plunger and its associated parts can be removed from the body portion in which it is mounted rapidly, conveniently and efficiently for the purpose of renewing and inserting a new valve to replace a valve that has become defective or deteriorated.

Another object of this invention is to provide means to so construct and combine the plunger and valve and its operating mechanism whereby the valve operating lever and ball carried thereby can be adjusted to any angular relation with respect to the water tank so as to provide means for aligning the valve operating lever and ball with respect to the tank as desired, without bending the lever.

Another object is to provide means for packing the plunger rod by the use of an integral resilient or yielding ring shaped washer and affording facilities for pressing the washer in close contact with the plunger rod to prevent leakage from the valve.

A further object is to provide means for compressing a packing ring which means is also adapted to permit the head or cap upon which the operating mechanism of the valve stem is mounted to be revolved to any predetermined angle with respect to the water closet tank or the like and rigidly hold and fasten the combined head and closure cap at such predetermined angle or position.

Another object is to provide a simple means for constructing a ball cock and its operating mechanism for the purpose intended of a minimum number of parts, thereby saving material and labor in the construction of same.

A further object is to provide means for reciprocating a plunger rod and plunger to prevent undue friction or binding effect on same, also to provide means for adjusting the downward throw of the trip lever and ball.

These and other objects are attained by the mechanism illustrated in the accompanying drawings in which:—

Figure 1 is a vertical section in elevation

of a ball cock showing the invention applied thereto.

Figure 2 is a side elevation of the invention assembled, preparatory to inserting same in the body or casing.

Figure 3 is a vertical sectional elevation of the casing showing it connected to the stand pipe.

Figure 4 is an elevation of the casing shown partly in section and also showing an end view of a portion of the operation mechanism of the plunger and valve.

The drawings are conventional and show the invention in a conventional manner applied to a conventional stand pipe 1 having a screw threaded end 2. The other end of the stand pipe is connected to a conventional type of coupling or clamping mechanism (not shown). The upper end of the stand pipe has its periphery screw threaded to threadably engage a union or cap 3. The union is interiorly screw threaded to engage the upper end of the stand pipe.

An aperture 4 is provided in the central portion of 4¹ of the union or cap and a portion 5 of the cap is raised surrounding the aperture to provide a valve seat 6. The union is exteriorly screw threaded to threadably engage the interiorly threaded body or casing 7 at the point indicated by reference numeral 8.

The body 7 is bored at 9 and counter-bored to a larger diameter at 10 to form a shoulder 11. A boss 12 is formed on the body and is provided with an interiorly threaded aperture to receive a thumb screw 13.

A closure cap 14 for closing the opening in the top of the body is provided and a depending portion 15 is provided thereon to fit the counter-bored portion 10. A groove 16 is formed on the periphery of the depending portion 15 preferably tapered or formed of inclined contour in cross section. The closure cap has an aperture formed at 17 in the central portion thereof of small diameter to receive a valve stem.

The depending portion of the closure cap is counter-bored larger in diameter than the small aperture or opening, to receive a felt or other resilient washer 18 or the like. The depending portion of the cap is bored to a depth that will leave a portion of the felt washer or the like extending beyond the end (or bottom face) of the depending portion,

for a purpose that will be described hereinafter.

The closure cap is also provided with a vertical supporting standard 19. A plunger rod 20, having an eye 21 formed on one end and having its opposite end screw threaded at 22 is provided. A plug 23 having an internal screw threaded aperture is provided to threadably engage the end of the plunger rod. The plug 23 has a portion of its periphery threaded as shown at 24 to threadably engage a combined plunger and valve holder 25 which is internally screw threaded and adapted to engage with the threaded portion of the periphery of the plug 23.

The combined plunger and valve holder 25 is provided with an aperture 26 and a valve 27 is fitted within the combined plunger and valve holder for cooperation with the valve seat 6. The valve 27 is securely retained and held in position in the combined plunger and valve holder by contact with the end of the plug 23 when the combined plunger and valve holder is screwed thereon. The valve is held in position under pressure of the combined plunger and valve holder against the end of the plug.

A metallic washer 28 is slidably fitted to the valve stem and is located between the combined plunger and valve holder 25 and the closure cap 14, and is supported on the shoulder 11. The projecting portion of the felt washer 18 is adapted to be forced in contact with the metallic washer 28. The closure cap 14 is swivelly and yieldingly supported on the metallic washer when the parts are assembled and inserted in the body. The plunger rod 20, the combined plunger and valve holder 25 and valve are operated by the following mechanism:

A bifurcated lever 29 is pivotally attached to the vertical standard 19 preferably by a cotter pin 30 or the like. At one end of the bifurcated lever a link 31 is pivotally attached thereto by a cotter pin 30 or the like. The lower end of the link is preferably bifurcated and connected to the eye 21 of the plunger rod 20 by a cotter pin 30 or the like.

It will be noted that the lever when moving up and down reciprocates the plunger in the portion 9 of the body or casing.

It will also be apparent that the link 31 is connected to the bifurcated lever so as to permit it to swing back and forth to accommodate or align the plunger rod with the bearings through which the plunger rod 20 operates, thereby eliminating undue friction or binding effect thereon. A boss 32 is provided on the lever 29 and a screw threaded aperture is provided therein to receive a screw 33 by means of which the downward throw of the valve operating lever 34 is regulated or adjusted. This is accomplished by adjusting the screw 33 which contacts with the vertical standard 19 and stops the

lever's downward movement at the predetermined point of adjustment.

The bifurcated lever 29 at its free end is provided with a screw threaded aperture 35 to engage with one end of the valve operating lever 34 and carries a ball 36 or the like. When the parts are assembled to be inserted in the body portion as shown in the drawings, the parts are in the first instance supported by the felt or the resilient integral ring shaped washer 18 which is supported on a metallic washer both washers being fitted to slide over the plunger rod 20 before assembling same for use.

The projecting portion of the felt washer 80 is supported by the metallic washer 28. When it is desired to regulate the angular relation of the bifurcated lever 29 with respect to the water closet tank to a predetermined position in the water tank, the closure cap 14 is revolved to the desired angular relation with respect to the tank and is held in the adjusted position by the manipulation of the thumb screw 13, the end of which is tapered and made to engage the tapered wall of the groove 16 formed in the depending portion 15 of the closure cap, thereby holding the cap in the desired predetermined position.

The end of the thumb screw 13 is so 95 formed and positioned, that it will engage the lower portion of the inclined wall of the groove 16 and force the closure cap 14 and resilient washer 18 downward against the metallic washer 28 or the like compressing the resilient washer and forcing it to expand in close contact with the plunger rod 20, thereby preventing any leakage from the valve past the stem through the closure cap 14.

When it is desired to remove the plunger, its associated parts and the operating mechanism from the casing, all that is necessary to do is to withdraw the end of the thumb screw 13 from its engagement in the groove 16 and all the parts can be removed in their entirety, for any purpose desired and afterwards replaced.

A boss 37 is provided with an aperture 115 therein which communicates with a chamber 38 which surrounds the end of the plunger carrying the valve. It is also provided with an aperture 39 which is used to receive the end of a refill pipe 40. The pipe 40 can be bent over the fulcrum 41 to any desired position in the tank. When desired to renew the valve, the combined plunger and valve holder is disengaged from its threaded connection to the plug 23 and a new valve placed therein.

It is not intended to limit the invention to the construction shown in the drawings, as many alterations or changes of the construction may be made without deviating from the principle of the invention.

I claim.

1. In a ball cock for water closet tanks, a body portion internally counter-bored to form a shoulder, a stand pipe having a valve seat member mounted thereon and secured to the body portion, a closure cap having a depending portion adapted to fit into and close the upper portion of the body, a plunger rod slidably mounted in said cap, a combined plunger and valve holder carried by its lower end, a valve carried by the combined plunger and valve holder which is adapted to contact with the aforesaid seat, a standard made integral with said closure cap and a lever pivotally mounted upon said standard, a link pivotally connected to the plunger rod and lever, whereby said plunger can be reciprocated as and for the purpose described.
2. In a ball cock for water closet tanks, a body portion internally counter-bored to form a shoulder, a stand pipe having a valve seat member mounted thereon and secured to the body portion, a revolving closure cap having a depending portion adapted to fit into and close the upper portion of the body, a plunger rod slidably mounted in said cap, a combined plunger and valve holder carried at its lower end, a valve carried by said plunger and adapted to contact with the aforesaid seat, a standard made integral with said closure cap, a lever pivotally mounted upon said standard, and a link pivotally connected to the plunger rod and lever whereby said plunger can be reciprocated as and for the purpose described.
3. In a ball cock for water closet tanks, a body portion internally counter bored to form a shoulder, a washer supported on said shoulder, a stand pipe having a valve seat member mounted thereon and secured to the body portion, a revolving closure cap having a depending portion adapted to fit into and close the upper portion of the body and counter bored, a resilient washer fitted within the counter bored portion, a plunger rod slidably mounted in said cap and slideable through said washers, a combined plunger and valve holder carried at its lower end, a valve carried by said plunger and adapted to contact with the aforesaid seat, a standard made integral with said closure cap, a lever pivotally mounted upon said standard, and a link pivotally connected to the plunger rod and lever whereby said plunger can be reciprocated freely as and for the purpose described.

4. In a ball cock for water closet tanks, a body portion internally counter bored to form a shoulder, a stand pipe having a valve seat member mounted thereon and secured to the body portion, a rotating closure cap having a depending portion adapted to fit into and close the upper portion of said body portion, a metallic washer supported on said

shoulder formed within the body portion between the depending portion of the closure cap and the valve, a resilient washer mounted on the metallic washer, said closure cap having a groove formed in a portion thereof, and means to engage in the groove whereby a downward movement may be imparted to the closure cap.

5. In a ball cock for water closet tanks, a body portion internally counter bored to form a shoulder, a stand pipe having a valve seat member mounted thereon and secured to the body portion, a revolving closure cap having a depending portion adapted to fit into and close the upper portion of said body portion, a metallic washer supported on said shoulder formed within the body portion between the depending portion of the closure cap and the valve, a resilient washer mounted on the metallic washer said closure cap having a groove formed in a portion thereof, and means to engage in the groove whereby a downward movement may be imparted to the closure cap, said closure cap being adapted to be revolved to position the parts carried thereby to any angular position with relation to the water closet tank.

6. In a ball cock for water closet tanks, a body portion internally counter bored to form a shoulder, a washer supported on the shoulder, a stand pipe having a valve seat member mounted thereon and secured to the body portion, a closure cap fitted to the body portion and adapted to be rotated, and also having a depending counter-board portion, a resilient ring washer fitted within the counter-bored portion to extend below the face of the depending portion, a plunger rod slidably mounted in said closure cap and slideable through said washers, a combined plunger and valve holder carried by the plunger rod, a valve carried by said plunger and adapted to contact with the aforesaid valve seat member, a standard made integral with said closure cap, a lever pivotally mounted upon said standard, and a link pivotally connected to the plunger rod and lever, whereby said plunger can be reciprocated, said closure cap and its associated mechanism being arranged to be removed in its entirety without disassembling same.

7. In a ball cock for water closet tanks, a body portion internally counter bored to form a shoulder, a washer supported on the shoulder, a stand pipe having a valve seat member mounted thereon and secured to the body portion, a closure cap adapted to be revolved and also having a depending counter bored portion, adapted to fit into and close the upper portion of the body, a resilient ring washer fitted within the counter bored portion and extending below the face, a plunger rod slidably mounted in said closure cap and slideable through said washers, a combined plunger and valve holder carried by the free

end of the plunger rod, a valve carried by said plunger and adapted to contact with the aforesaid seat member, a standard made integral with said closure cap, a lever pivotally mounted upon said standard and a link pivotally connected to the plunger rod and pivoted lever, whereby said plunger can be reciprocated, said closure cap and valve and operating mechanism being arranged to permit its removal in its entirety without disassembling same and means to compress the resilient washer.

8. In a ball cock, a stand pipe, a valve casing connected to said pipe, a valve seat in the casing, a counterbored closure cap fitted to the casing, a resilient washer fitted within the counter bore formed in the closure cap and extending below the face thereof, a metallic washer supported in the casing, means to exert a downward movement on the closure cap to compress the resilient

washer against the metallic washer, a combined plunger and valve holder, a valve carried by the plunger, and means to reciprocate the combined plunger and valve holder, said means including a stem extending through said washers and closure cap, as described and set forth.

9. In a ball cock for water closet tanks, a valve casing provided with an interior shoulder, a washer supported on the shoulder, a counter bored closure cap having an opening therein for receiving a valve operating rod and fitted to the casing, a resilient washer having an opening therein in alignment with the opening in said cap and fitted within the counter bore of the closure cap and adapted to engage the first named washer, so as to yieldingly support the closure cap, as and for the purpose described.

In testimony whereof I affix my signature.
CHARLES HUBBARD BERRY.
